(57) **CLAIM**

The ornamental design for a mattress with a removable mattress topper assembly, as shown and described.

DESCRIPTION

FIG. 1 is a top plan view of the mattress with a removable mattress topper assembly of the present design;

FIG. 2 is a bottom plan view of the mattress with a removable mattress topper assembly of FIG. 1;

FIG. 3 is a front elevational view of the mattress with a removable mattress topper assembly of FIG. 1, the rear view of the mattress with a removable mattress topper assembly being a mirror image thereof;

FIG. 4 is a left side elevational view of the mattress with a removable mattress topper assembly of FIG. 1, the right side view of the mattress with a removable mattress topper assembly being a mirror image thereof;

FIG. 5 is a perspective view of the mattress with a removable mattress topper assembly of FIG. 1;

FIG. 6 is a perspective view of the mattress with a removable mattress topper assembly of FIG. 1, showing the mattress topper removed from the mattress; and,

FIG. 7 is an enlarged detail view of the mattress with a removable mattress topper assembly taken from the encircled portion labeled 7 in FIG. 5.

1 Claim, 6 Drawing Sheets
